UNITED STATES PATENT OFFICE.

LEWIS C. MALTBY, OF WASHINGTON, DISTRICT OF COLUMBIA, ASSIGNOR TO THE STONE STRAW COMPANY, OF WASHINGTON, DISTRICT OF COLUMBIA, A CORPORATION OF NEW JERSEY.

MECHANISM FOR CUTTING TUBES.

1,201,842.

Specification of Letters Patent. Patented Oct. 17, 1916.

Application filed February 21, 1916. Serial No. 79,755.

To all whom it may concern:

Be it known that I, LEWIS C. MALTBY, a citizen of the United States, residing at Washington, in the District of Columbia, have invented certain new and useful Improvements in Mechanism for Cutting Tubes, of which the following is a specification.

My invention relates to an improved mechanism for cutting tubes into lengths.

The dominant idea presented by this invention is the provision for causing the cutting disk to revolve and travel in its circular orbit at a high speed, and while so doing to turn on an axis which will insure its withdrawal from the path of the rapidly oncoming tube or straw at a speed co-extensive at least therewith.

This invention, therefore, comprises mainly a disk cutter mounted to turn on three different axes, as well as in other auxiliary features of construction which will be hereinafter described and pointed out.

In the accompanying drawings:—Figures 1 and 2 are vertical sectional views taken at right-angles to each other; Fig. 3 is a horizontal section; Fig. 4 is an enlarged sectional view through the disk or cutter, its gear, the rotary head which supports it, showing its bearing in elevation; and Fig. 5 is an enlarged fragmentary detail of one edge of the rotary head.

A, represents the machine-bed or frame, to which the casing 1 is securely held by the bolts 2. A vertical shaft 3 is rotatably supported in the sleeve 4 at the base of the casing 1, and to its lower end a spiral gear 5 is secured by the nut or equivalent means 5'; and a smaller spiral-gear 6 secured on the drive-shaft 7 transmits motion to the spiral gear 5, and through it to the vertical shaft 3, as shown in Figs. 1 and 2.

A housing 8 is secured to the upper end of the vertical shaft 3, by means of a pin 9, and a horizontal shaft 10 is journaled in bearings 11 extending transversely of the housing. A bevel-gear 12 is secured on one end of this horizontal shaft 10, and its teeth mesh with the teeth of an annular crown gear 13 secured and depending from the cover 14, which is hinged at 15 to the casing 1, as shown in Fig. 1. By this means the shaft 10 is rotated as the casing 8 is turned on its vertical axis. A circular head 16 is

held fast to the shaft 10 by a pin 17, passing through its hub and the shaft 10. The disk cutter 18 is carried by this head 16, it being rigidly connected thereto by any approved means, as, for instance, that shown in detail in Figs. 4 and 5, in which a notch 19 in the head 16 has a countersunk inner face 20, which receives the hub 21 of the axle 22 bolted to the head by the nut 23 secured on the threaded end 24 of the axle. Mounted on this axle with interposed ball-bearings 25, is a gear 26, and upon the hub of this gear the disk or cutter 18 is securely held by the nut 27 screwed on the threads 28 of the hub, as clearly illustrated in Fig. 4. The teeth of the disk or cutter-gear 26 mesh with the teeth of the large stationary gear 29, which is mounted concentric with the shaft 10, and secured to one of the bearings 11 by the angle-plate or other means 30 bolted to the bearing and the gear 29, as at 31, see Figs. 2 and 3.

Clearance slots 32 and 33 are provided on opposite sides of the housing 8 for the disk or cutter 18 as it passes these points, while the top portion 34 of the housing forms a safety-guard, although it is understood that since the crown teeth 13 are carried by the cover 14, that on lifting the latter the power which drives the shaft 10 is removed, although the vertical shaft 3 will continue to spin until the drive-shaft 7 stops.

The straw-guides 35 and 36 are located in position to receive the formed tube or straw S, which is fed rapidly therethrough, and which is severed into predetermined lengths by the disk-cutter 18, which not only is revolving at a high speed, but which likewise is swinging around on its vertical axis 3 at a speed of six to one, or in other words the rotary disk cutter 18 is traveling around the stationary wheel 29 just six times to one complete revolution of the housing 8. In this way, not only is the disk-cutter revolving at a rapid rate, but it is also traveling through its rotary orbit around the stationary gear 29 at a high rate of speed, and while the rotation of the axle 3 and the housing 8 secured thereto is one-sixth as great, it is still equal to that of the progressive forward movement of the tube or straw to be cut, so that as it severs the latter into predetermined lengths with exactness and precision, it at the same time gets out of its way

faster than the straw feeds forward, thus giving a quick forward brush to the severed end of the straw tending to brush it out of guide 36.

5. I claim:

• 1. In a cutting machine, the combination of a disk-cutter, means whereby the disk may be rotated and caused to travel in a common plane, and a rotary support for said means, the axis of rotation of which lies parallel to the plane of rotation and travel of the disk-cutter.

10 2. The combination of two shafts, one carried by the other at an angle thereto, a disk-cutter revoluble about its axis and rotatable about the axis of the carried shaft, both movements being in a plane parallel with the longitudinal axis of the other shaft, and means for rotating said shafts.

15 3. The combination of two rotatable shafts, one carried by the other at a right angle thereto, a disk-cutter mounted for rotation with and about the axis of the carried shaft and about its own axis, said rotations being in a plane parallel with the longitudinal axis of the other shaft, and means for rotating both of said shafts.

20 4. The combination of two rotatable shafts, one carried by the other at an angle thereto, a disk-cutter mounted for rotation with and about the axis of the carried shaft and about its own axis, said rotations being in a single plane, and means for rotating both of said shafts.

25 5. In a cutting machine the combination of a rotatable shaft, a pivotal support therefor, a rotary disk-cutter mounted on said shaft for rotation therewith, the axis of rotation of said cutter lying parallel to the longitudinal axis of said shaft, and means for rotating said shaft and turning the same about its pivotal support.

30 6. The combination of a rotatable shaft, a head carried thereby, a disk cutter rotatably connected with the head, means for turning the shaft bodily with its support, means for causing an axial rotation of the shaft while it is being turned bodily, and means for rotating the disk cutter on its own axis as a result of its rotation about the axis of the shaft.

35 7. The combination of a rotatable shaft, a second shaft carried by the first-named shaft, a head secured to the latter-named shaft, a disk-cutter rotatably connected with the head, and means concentric with the last-named shaft for revolving the disk-cutter as the shaft is turned.

40 8. The combination of a rotatable shaft, a second shaft carried by the first-named shaft, a head secured to the latter-named shaft, a disk cutter rotatably connected with the head, means concentric with the last-named shaft for revolving the disk cutter as the shaft is turned, and means which ro-

tates the last-named shaft as the latter is carried around by the rotation of the first-named shaft.

9. The combination with a rotatable shaft, bearings supported thereby, a shaft journaled in said bearings and carrying a head, and having a stationary toothed wheel concentric therewith, a disk cutter rotatably supported on the head and having a gear, the teeth of which mesh with the teeth concentric with the shaft which carries the head for rotating the disk cutter, and means for causing the shaft which carries the head to revolve as it is carried around by the first-named shaft as it is turned.

the countersink, means for securing said axle to the head, a gear on the axle, ball-bearings and a disk-cutter removably secured to the hub of the gear.

5 14. The combination with a casing having straw-guides, through which the tube or straw is fed, of two rotary shafts at an angle to each other, one supported by the other, means for rotating both of said shafts, a ro-

tary disk cutter carried by one shaft and 10 caused to travel in an orbit thereby, and means for revolving said disk cutter and periodically carrying it across the path of the tube or straw and laterally at a speed as great as the on-moving tube or straw. 15

In testimony whereof I affix my signature.

LEWIS C. MALTBY.
